UNITED STATES PATENT OFFICE.

JOHN BRUCE MACKAY, OF WATERLOO, IOWA.

MAUSOLEUM.

1,008,421.

Specification of Letters Patent. Patented Nov. 14, 1911.

Application filed April 17, 1911. Serial No. 621,573.

To all whom it may concern:

Be it known that I, JOHN BRUCE MACKAY, a citizen of the United States of America, and a resident of Waterloo, 5 Blackhawk county, Iowa, have invented certain new and useful Improvements in Mausoleums, of which the following is a specification.

My invention relates to improvements in 10 mausoleums, and the object of my improvements is to provide a particular arrangement of the crypts within the building, especially to vary the location of certain of the crypts with relation to the others as to 15 render them more convenient of access and adapted by suitable means for the inspection of bodies entombed therein, and otherwise and equally to furnish to all the crypts certain suitable and effective means for de- 20 odorizing gases generated within, and disinfecting fluids seeping from the entombed remains, as also supplying in each crypt substances capable of evolving germicidal vapors. These objects I have accomplished 25 by the means which are hereinafter described and claimed, and which are illustrated by the accompanying drawings, in which:

Figure 1 is a vertical longitudinal section taken medially through my improved mausoleum building on the line *e-f* of Fig. 2. Fig. 2 is a vertical transverse section of said building taken on the line *g-h* of Fig. 1. Fig. 3 is a horizontal section of the left-hand half of said building, taken on the line 35 *a-b* of Fig. 1. Fig. 4 is a horizontal section of the same half of said building, taken on the line *c-d* of Fig. 1. Fig. 5 is an enlarged detail view in vertical longitudinal section, of a portion of one of the crypt floors, together with the well containing disinfecting material embedded therein. Fig. 6 is an enlarged detail of a portion of the wall of a crypt, showing the bracketed 40 receptacle for holding a charge of germicidal material.

Similar numerals of reference designate corresponding parts throughout the several views.

The roof 5, walls 6, foundations 8 and 50 complete underfooting 7 are constructed of reinforced concrete, with windows at either end lighting a medial longitudinal hall 18. The hall 18 is of suitable proportions to be used conveniently as a chapel wherein may 55 be held funeral services in commemoration

of persons deceased and to be entombed in a crypt of the mausoleum.

The crypts are built of reinforced concrete, having removable concrete front walls 21 provided with facing-plates 22 of marble or other suitable materials. The floor of each crypt is formed to present a concavity of hollow 10 at whose lowest part is hollowed a well containing a receptacle 11 containing an active disinfecting substance 65 adapted to act destructively upon fluids seeping from a decomposing body in the crypt. The open upper end of the receptacle 11 may be covered by a grating or perforated plate when desired. In each crypt one or more receptacles 9 are bracketed to the walls, and filled with formaldehyde or any other substance capable of giving off germicidal vapors to act upon the air of the crypt or upon the body therein to destroy bacteria 70 or other germs. Furthermore, each crypt is supplied with a receptacle 12 having an inlet adapted to receive gases from a decomposing body and pass the gases through some suitable deodorizing composition or 75 substance in the receptacle and then out of the building by way of pipes 13 and 14.

We have adopted in the mausoleum a new and convenient method of arrangement of the crypts. The two upper tiers of crypts 80 1 and 2 register or align vertically, with their front walls forming the general walls of the sides of the medial apartment 18. The tier of crypts 3, however, are longitudinally displaced relatively to the crypts 1 and 2 thereover, so as to project their front ends into the hall or apartment 18 a certain distance, for a purpose to be described hereinafter. Two rows of crypts 4, lie side by side entirely covered beneath the floor of the 85 apartment 18. The crypts 4 are roofed by slabs 19 of concrete, the slabs being then overlaid with flooring 20 of wood or other materials.

Referring especially to Figs. 2 and 3, it 90 will be seen that the roof slab of each crypt 3 extends into the apartment 18 for a sufficient distance to permit of the insertion therein of a rectangular opening 16 closed by two spaced apart and sealed transparent closures 15, the sealing of same being hermetic. The location of these openings is such that each opening is over the head of the remains of a decedent lying in a coffin 95 underneath. A cover 17 may be used to 100

105

110

place over said opening, and then removably secured in any convenient way. Corpses which are unidentified may thus be placed in the crypts 3 and kept until identified, inspection being permitted by means of the windows thus provided. The ledges or shelves thus provided in the apartment 18 may be further utilized for the reception of vases of flowers, other funerary emblems, or inscriptions as desired. The arrangement of the crypts thus permits their use for several purposes as desired, while the individual crypts are each disinfected and deodorized and placed in an innocuous condition and thus all adapted to preserve bodies entombed therein for a maximum limit of time without the communication of infection to living persons.

Having described my invention, what I claim as new, and desire to secure by Letters Patent, is:

1. In a mausoleum, an apartment or passage-way, a crypt abutting thereon, and a crypt under the other crypt and displaced relatively thereto longitudinally to project therehence into the passage-way a desired distance, said latter crypt being provided in its projected portion with a glazed opening for permitting a view therethrough of the features of a body interred therein.

2. In a mausoleum, an apartment or passage-way, a crypt abutting thereon, a crypt under the other crypt and displaced relatively thereto longitudinally to project therehence into the passage-way a desired distance, said latter crypt being provided in its projected portion with a glazed opening for permitting a view therethrough of the features of a body interred therein, and a third crypt located near said second-mentioned crypt but situated wholly below and underneath the floor of said apartment or passage-way.

3. A mausoleum, comprising a structure containing an apartment surrounded by a plurality of crypts, certain of the crypts being located partially under others but longitudinally displaced so as to project therehence bodily into the apartment to form a shelf or ledge, the projecting parts having sealed windows therein permitting a view of the features of bodies therein, and means for removably covering said windows.

Signed at Waterloo, Iowa, this 30th day of March, 1911.

JOHN BRUCE MacKAY.
